UNITED STATES PATENT OFFICE.

FRED L. McGAHAN, OF INDIANAPOLIS, INDIANA.

BOILER-FLUE CLEANER.

SPECIFICATION forming part of Letters Patent No. 367,826, dated August 9, 1887.

Application filed December 18, 1886. Serial No. 221,968. (No model.)

To all whom it may concern:

Be it known that I, FRED L. McGAHAN, a citizen of the United States, residing at Indianapolis, in the county of Marion and State 5 of Indiana, have invented a new and useful Improvement in Boiler-Flue Cleaners, of which the following is a specification.

My invention relates to improvements in an improved boiler-flue cleaner for which Letters Patent No. 313,509 were issued to me March 10, 1885. Said flue-cleaner is of that 10 class in which the flue is cleaned by means of a jet of steam suddenly and forcibly discharged through a suitable nozzle, by means of which 15 it is directed against and along the interior walls of the flue, the discharge of steam into the flue being controlled by means of a valve which is automatically closed by the steam-pressure when the cleaner is removed from the 20 flue.

The objects of my present improvements are to provide means whereby the act of pressing the nozzle into and against the open end of the flue will operate to draw the valve open 25 from the rear, as well as to push it from the front; to provide means for sustaining the nozzle centrally in a flue of considerably larger diameter than the nozzle, and to provide for the discharge of an additional central jet of 30 steam, all as hereinafter fully described.

The accompanying drawings illustrate my invention.

Figure 1 represents a longitudinal section; Fig. 2, a front elevation; Fig. 3, a rear elevation, and Fig. 4 a perspective view of one of the details.

A is the nozzle having a series of narrow annular discharge-ports, b b b. The interior walls of said discharge-ports are inclined to 40 the axis of the nozzle, so as to direct the steam-jets issuing therefrom at a sharp angle against the interior walls of the flue.

B is a flat annular plate arranged to slide over the nozzle, and connected by four arms, c, with 45 a central hub, d, which is secured by a nut, e, to the valve-stem f.

F is the valve, which is opened by the backward movement of the plate B, thus allowing the steam to pass from the steam-chamber h 50 to the ports b.

H is a tube forming the handle of the de-

vice and connecting the steam-chamber h with a T-coupling, k, having its outer lateral branch closed by the stuffing-box i.

To the vertical branch j of coupling h, I attach a hose or a system of swivel-jointed pipes, connecting the cleaner with the boiler or other source of steam-supply.

I is a rod connected at one end to the valve F and passing rearwardly through tube H and 60 stuffing-box i, the purpose being to enable the operator to pull the valve open from the rear.

L is a short vertical handle secured by a clip, m, to tube H.

The parts above described are all shown in 65 my above-mentioned Letters Patent.

I have found in using my device as at first constructed that when the nozzle is made of sufficient size to fill the end of a flue more than five or six inches in diameter the implement 70 becomes too heavy to be easily handled, and when the valve is made large enough to admit the necessary amount of steam to clean such a flue successfully that considerable effort is required to open the valve against the steam-pressure. I have found, also, that in a large flue, in order to get the best results from the annular jets of steam discharged through the ports b, it is desirable to supplement those jets with a central jet which shall operate to fill 75 the central portion of the flue. To remedy the first of these difficulties, I use the same-sized nozzle for all flues above six inches in diameter, only making the plate B of sufficient size to fully cover and close the end of the flue. 80 For the purpose of sustaining the nozzle in a central position in a flue of larger diameter than the nozzle, I form on the face of the plate B an annular flange, l, which is arranged concentrically with the nozzle and is of such external diameter as to fit easily within the flue. 85 By the use of different-sized plates B the same cleaner may be used in different-sized flues.

It will be observed that if the operator attempts, after placing the nozzle in the end of the flue N, to assist the opening of the valve F by pulling outward directly on the exposed end of the rod I, while pushing inward against the handle L, that his force will be expended 90 mainly between those two points and he cannot therefore hold the plate B steadily and 100

firmly against the end of the flue. I therefore pivot a lever, *n*, to an arm, *o*, which is secured to the coupling *k*. The upper end of lever *n* is forked and engages rod *I*, and the lower end projects below the arm, so that a push toward the nozzle on the lower end of the lever operates to draw the rod outward. By this construction the whole force of the operator is exerted in one direction to open the valve.

10 For the purpose of enabling the operator to swing lever *n* and arm *o* to the right or left, so as to bring the lever to the most convenient position, a collar, *p*, is formed on the coupling *k* and arm *o* is formed integral with two like parts, *r* and *s*, Fig. 4, which, when secured together, form a circular yoke which is adapted to embrace and turn easily upon the collar *p*.

For the purpose of providing a central jet of steam, the valve-stem *f* is made hollow and 20 provided with several openings, *u u*, communicating with its interior, the outer end of the stem being open and the inner end closed by the valve.

In operation, the cleaner having been connected with a source of steam-supply, thus admitting steam to the tube *H* and valve-chamber *h*, the operator seizes handle *L* with one hand and lever *n* with the other hand. Then inserting flange *l* in the open end of the flue, 30 he pushes plate *B* strongly against the end of the flue or the boiler, and the nozzle moves forward, thus carrying the valve-seat away from the valve. At the same time the thrust against the lower end of lever *n* operates 35 through rod *I* to draw the valve away from its seat.

It is obvious that under a moderate pressure of steam the valve may be opened by the lever alone. The steam, passing the valve, rushes 40 with a sudden blast through the hollow stem *f* and the annular ports *b* into the flue and along its walls, thus removing all soot and ashes.

I claim as my invention—

45 1. In a flue-cleaner, the combination, with the cylindrical nozzle having divergent annular discharge-ports, the valve-stem, the valve seated within the nozzle, and the annular plate

connected by radial arms with the valve stem and arranged to slide longitudinally on the 50 nozzle, of the annular flange formed on the face of the said plate, and arranged concentrically with the nozzle, whereby the nozzle is centrally supported in a flue of large diameter, substantially as specified.

2. The combination, with the nozzle, the tube connected therewith, the short handle *L*, the interior valve, the valve-stem, and the annular plate connected to the valve-stem and arranged to slide on the nozzle, of the rod extending from the valve backward through the tube, the arm secured to the tube, the lever pivoted to the arm and arranged to engage the rod, and forming a second handle whereby the cleaner is held and the valve is opened by 60 the operator pushing simultaneously against both of said handles, substantially as specified.

3. In a boiler-flue cleaner operating substantially as described, the coupling *k*, having collar *p*, the arm *o*, having the yoke adapted 70 to embrace the collar and to turn on the coupling, the lever pivoted to the arm, the rod, and the valve, all combined and arranged to co-operate as and for the purpose specified.

4. In a flue-cleaner, the combination, with 75 the hollow cylindrical nozzle having divergent annular discharge-ports, the valve, and the sliding annular plate, of the hollow perforated valve-stem connecting the valve and the plate, and arranged to operate substantially 80 as specified.

5. The combination, with the nozzle, the tube connected therewith, the handle *L*, secured to the tube, the interior valve and the rod extending from the valve backward 85 through the tube, of the arm secured to the tube, the lever pivoted to the arm and arranged to engage the rod, and forming an auxiliary handle, *B*, whereby the nozzle is thrust into the flue and the valve is simultaneously opened by the operator pushing against 90 the handles, substantially as specified.

FRED L. McGAHAN.
